Patented Dec. 26, 1911.

Wm. H. Smith
Bertha M. Allen.

UNITED STATES PATENT OFFICE.

THOMAS J. MOORE, OF RICHMOND HILL, NEW YORK

MAUSOLEUM.

1,012,893.

Specification of Letters Patent. Patented Dec. 26, 1911.

Application filed July 1, 1911. Serial No. 636,474.

To all whom it may concern:

Be it known that I, THOMAS J. MOORE, a citizen of the United States, residing at Richmond Hill, in the borough of Queens, 5 city and State of New York, have invented an Improvement in Mausoleums, of which the following is a specification.

My invention relates to a tomb or mausoleum above ground, containing a series 10 of catacombs, and adapted for the reception of a plurality of bodies, such as shown in Letters Patent No. 863,303, granted to me August 13, 1907, but my invention is applicable to many different constructions of 15 tombs or mausoleums, and it consists in providing means whereby the gaseous products of decomposition may be conveyed from the catacombs to the atmosphere exterior of the mausoleum, while the fluid products of 20 decomposition are conveyed to earth or discharged directly into a sewer below the catacomb, and whereby both such products may be conveyed from any one or all of the catacombs simultaneously.

25 It further consists in providing means whereby any such products of decomposition that may be issuing from one or more of the catacombs is prevented from entering another catacomb in which an interment 30 may or may not have been made.

It is preferable to so arrange the parts that there are no projections beyond the inner surfaces of the catacombs, and therefore no interference with the placing of a 35 casket and its retaining box into the catacomb, while at the same time the parts are not visible on the exterior of the catacombs and consequently there is nothing to mar the ornamental appearance of the structure.

40 In the accompanying drawing, Figure 1 is a vertical transverse section of a mausoleum fitted with my improvement and showing the system of pipes therein in elevation. Fig. 2 is a horizontal section at 45 about the dotted line α , α , of Figs. 1 and 3. Fig. 3 is a vertical section at about the dotted line y , y , of Fig. 2, and Fig. 4 is a broken plan view of one of the bottom slabs. The parts in Figs. 2 and 3 are shown in larger 50 size.

Similar reference numerals indicate corresponding parts in all the figures of the drawing.

1 represents the foundation wall; 2 the 55 side walls; 3 the back and front walls; 4 the roof slabs, and 5 the roof key-stone.

The roof slabs and key-stone are each preferably in one piece, the full length of the mausoleum or vault, there being a series of recesses 6 in the faces of the keystone 60 which abut the edges of the roof slabs, and other recesses 7 in the upper face of each roof slab adjacent to the edge thereof coming against the keystone, so that when the parts are assembled, the respective recesses 65 come into juxtaposition and form ventilating openings in the roof, which permit the passage of currents of air and prevent the entrance of water or snow in storms, a similar construction being shown in my aforesaid patent and also in Letters Patent No. 863,930, granted to me August 20th, 1907.

Within the foundation 1, I prefer to provide a bed of cinders 8, or other similar material, the upper surface of which is on the same level with the upper surface of the foundation, and upon this bed of cinders 9, and the foundation, I place a concrete bed 10.

10 represents a floor slab preferably in one piece from the front to the back wall of the 80 mausoleum. This floor slab rests upon raised portions 11 of the concrete bed, so that an air space is formed between the floor slab and upper surface of the concrete bed.

The catacombs are composed of the bottom shelves 12, intermediate shelves 12^a, top slabs 13, end slabs 14, front slabs 15 and back slabs 16, and are preferably so proportioned that each catacomb is a receptacle for a single body and its coffin and retaining box. 85

37 represents a cover slab which extends over the space between the catacombs and above the floor slab 10, and this cover slab is preferably supported on the edges of the top slabs 13 and front slabs 15. It is preferable that this cover slab 37 be provided with 90 openings, and that a ventilation device 38 be secured over the said openings.

The structure thus far described is similar to that shown in my aforesaid patents. 100

The inner surface of each of the end slabs 14 nearest the rear of the mausoleum is preferably provided with a uniting vertical recess 17 and transverse recess 17^a. Arranged within the vertical recesses 17, are sections of pipe 18, which pass through openings in the shelves 12, 12^a, and top slabs 13, and are united within each catacomb by a coupling 19. These pipes 18 form a conduit for gases and extend above the catacombs and along the under surfaces of the roof slabs 4 closely adjacent thereto, and terminate at a point 110 105

near the ventilating openings in the roof. These pipes 18 may be supported under the roof by bands or clamps 20, if desired, or in any suitable manner.

5 Within the transverse recess 17* in each catacomb at one side of the vertical pipe 18, is a branch pipe 21 connected with the pipe 18, by the coupling 19. The free ends of these branch pipes 21 are open and preferably flaringly outturned. In each of these branch pipes 21, at a point between their outturned open ends and the couplings 19, there is a tubular projection 22 of slightly larger interior diameter than the pipes 21, 15 which tubular projections are upwardly inclined in the direction of the pipes 18. The projections 22 are open-ended and exteriorly screw-threaded at their upper ends. A ball 23 of suitable material is inserted into each 20 of these tubular projections, and a cap 24 is then screwed over the upper screw-threaded ends of said projections, and if desired, a washer or packing ring or disk 25 may be employed to avoid any chance of 25 leakage at these points.

It will be readily understood that the gases produced by the decomposition of a body within the catacomb, will pass into the open end of the pipe 21 and force the ball 23 up the inclined inner surface of the tubular projection 22 (see Fig. 3), thus opening a passageway for the gases to the vertical pipe 18 through which they will be carried and conveyed into the atmosphere through 35 the ventilating openings in the roof. I prefer to employ a deflector 26 to aid in directing the gases from the pipes or conduits 18 into the ventilating openings in the roof. This deflector may be secured to the under 40 surface of the keystone in any suitable manner. It will also be obvious that when the pressure of the gases is relieved upon the balls 23, they will fall by gravity against their seats (as in dotted lines, Fig. 3), thus 45 closing the passageways into the catacombs against the ingress of gases that might be rising in the pipes 18 from a catacomb below, or of any other foreign substance.

It is also essential that the fluid products 50 of decomposition be conveyed from the catacombs, and I provide for this in the following manner:—The upper surface of the bottom slab of each catacomb is provided with a series of longitudinal grooves 27 and a 55 transverse groove 28, at or near one end with which the longitudinal grooves unite. These grooves 27 commence at the surface of the slabs near one end and gradually deepen as they extend toward the transverse groove 60 28, which groove is cut in a similar manner from one end to the other. Within the deeper end of each of said transverse grooves 28, there is an opening 29 which extends entirely through the bottom slabs, the lower 65 portion of such opening being of reduced

diameter forming a shoulder 30 within such opening in each bottom slab. Within the lower part of these openings 29, there are tubular members 31, provided at their upper ends with an annular flange 32, which rests 70 upon the shoulders 30. The lower ends of these tubular members extend slightly below the under surface of each bottom slab, and are exteriorly screw-threaded. Branch pipes 75 33 are connected at one end to the screw threaded ends of the tubular members 31, while their other ends are connected with the pipes 18 by the coupling 19. 34 represents tightening nuts. The branch pipes 80 33 are each provided with an automatic valve such as described in connection with the branch pipe 21, and upon which I have placed the same reference numerals.

It will be readily understood that any fluid products of decomposition escaping 85 into the catacomb, will run down the inclined longitudinal grooves on the bottom slabs and be directed by the transverse grooves into the openings 29 and branch pipes 33, and coming in contact with the 90 balls 23, will raise the same up the inclined inner surfaces of the tubular projections (see dotted lines, Fig. 3), and permit the passage of the fluid into the pipes 18, down which it will fall and by which it may be conveyed 95 to the earth or to any suitable receptacle. I have shown the lower ends of the pipes or conduits 18 as connected with a sewer 35, and it is preferred that check valves be employed at or near the lower ends of these 100 pipes to provide against the ingress of gases or other foreign substance.

It is preferable that the pipes 18 and branch pipes 21 and 33 be arranged in the recesses 17 and 17* as shown, in order that 105 there may be no projections beyond the inner surfaces of the catacombs and therefore no liability of the pipes being accidentally injured when placing a casket and its retaining box into the catacomb, but it is obvious that these pipes may be arranged within the catacombs close to the inner surface of the walls, and the recesses dispensed with without departing from the spirit of 110 my invention.

The catacombs may be washed out or be cleansed by the use of a hose or otherwise if desired, when the water and refuse will be carried away by the pipes 33 and 18.

The importance and advantages of the 120 employment of the automatic valves in the branch pipes 21 and 33 will be better understood by supposing that a burial has been made in the lower vault or catacomb. Upon decomposition of the body, the gaseous products will enter the flared open end of the branch pipe 21 and force the ball 23 up the inclined inner surface of the part 22, allowing the gases to pass into the vertical pipe 18 and ascend therein while any of such 130

gases that may enter the branch pipe 21 in a catacomb above will force the ball or balls 23 in such catacomb or catacombs more firmly against their seats, thus effectually preventing the ingress of such gases into such catacomb or catacombs, while any such gases that might pass across the opening in the pipe 18 into the branch pipe 33, will force the ball against its seat in a like manner and prevent the entrance of such gases into a catacomb above through the branch pipes 33.

I claim as my invention:

1. In a structure provided with a series 15 of compartments, a vertical conduit crossing and connecting the compartments of the series and communicating with the atmosphere at the top, a branch conduit in each compartment connected at one end to and 20 communicating with the interior of said vertical conduit, its other end being open and communicating with the next compartment above, and an automatic valve in each said branch conduit intermediate its open end 25 and said vertical conduit.

2. In a structure provided with a series 30 of compartments, a vertical pipe crossing and connecting the compartments of the series, a branch pipe in each compartment connected at one end to and communicating 35 with the interior of said vertical pipe, the free end of said branch pipe being open, an automatic valve in each said branch pipe intermediate its open end and said vertical 40 pipe, a second branch pipe in each compartment connected at one end to and communicating with the interior of said vertical pipe opposite to said first branch pipe, and an automatic valve in each said second branch 45 pipe intermediate its open end and said vertical pipe.

3. In a mausoleum adapted for the reception 50 of a plurality of bodies, the combination of catacombs arranged in series of tiers 55 with an opening in the top and bottom of each catacomb, a vertical pipe passing through said openings in each series of tiers, a branch pipe connected to and communicating 60 with the interior of each vertical pipe at the top of each series of catacombs and extending therefrom along underneath the roof of the mausoleum and communicating with the atmosphere, the said branch pipes being open-ended, a branch pipe in each 65 catacomb connected at one end to and communicating with the interior of said vertical pipes, the free end of each said branch pipe being open, an automatic valve in each said branch pipe intermediate its open end and 70 said vertical pipe, and a deflector for directing the gases to the atmosphere as such gases issue from the open ends of said branch pipes.

4. In a mausoleum adapted for the reception 75 of a plurality of bodies, the combination

of catacombs arranged in series of tiers with openings in the top and bottom slabs of each catacomb, a vertical pipe passing through said openings in each series of tiers, a branch pipe in each catacomb communicating 80 with said vertical pipe at one end and at the other end with the catacomb immediately above, an automatic valve in each said branch pipe, and a branch pipe connected to and communicating with the interior of 85 said vertical pipes beneath the bottom slab of the lowermost catacomb of each series of catacombs and extending beneath the mausoleum.

5. In a mausoleum adapted for the reception 90 of a plurality of bodies, the combination of catacombs arranged in series of tiers with openings in the top and bottom slabs of each catacomb, a vertical pipe passing through said openings in each series of tiers, a branch pipe connected to and communicating 95 with the interior of said vertical pipe at the top of each series of catacombs, the said branch pipes being open-ended and communicating with the atmosphere, a branch pipe connected to and communicating with the interior of said vertical pipe beneath the bottom slab of the lowermost catacomb of each series of catacombs and extending therefrom beneath the mausoleum, a branch 100 pipe in each catacomb communicating with the interior of said vertical pipe, the free end of each said branch pipe within the catacombs being open, an automatic valve in each said branch pipe, another branch pipe in each catacomb communicating at one end with said vertical pipe and at the other end with the catacomb immediately above, and an automatic valve in each said branch pipe.

6. In a mausoleum adapted for the reception 110 of a plurality of bodies, the combination of catacombs arranged in series of tiers with openings in the top and bottom slabs of each catacomb, a vertical pipe passing through said openings in each series of tiers, a branch pipe connected to and communicating 115 with the interior of said vertical pipe at the top of each series of catacombs, the said branch pipes being open ended and communicating with the atmosphere, a branch pipe connected to and communicating with the interior of said vertical pipe beneath the bottom slab of the lowermost catacomb of each series of catacombs and extending therefrom beneath the mausoleum, a branch pipe in each catacomb communicating 120 with the interior of said vertical pipe, the free end of each said branch pipe within the catacombs being open, an automatic valve in each said branch pipe, another branch pipe in each catacomb communicating at one end with said vertical pipe and at the other end with the catacomb immediately 125 above, an automatic valve in each 130

said branch pipe, and a deflector for directing the gases through an opening in the roof of the mausoleum as such gases issue from the open ends of the said branch pipes communicating with the upper ends of the said vertical pipes.

7. In a burial vault, a vertical conduit communicating with the atmosphere at the top, and extending below the vault, branch 10 conduits connecting therewith, automatic means located within the vault and communicating with said conduits whereby gaseous products of decomposition are per-

mitted to escape from the vault and the ingress of gases or foreign matter prevented, 15 and other means located beneath the vault, but communicating with the interior thereof and also with the said conduits whereby fluid products of decomposition are carried away from the vault.

Signed by me this 29th day of June, 1911.

THOMAS J. MOORE.
